(57) **CLAIM**

The ornamental design for a medical cleaning and disinfection apparatus, as shown and described.

DESCRIPTION

FIG. 1 is a perspective view of a medical cleaning and disinfection apparatus showing our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is an enlarged sectional view, taken along line 8-8 in FIG. 2 of the portion thereof indicated by line a-a in FIG. 7; and,

FIG. 9 is an enlarged sectional view, taken along line 9-9 in FIG. 4 of the portion thereof indicated by line b-b in FIG. 2. The broken lines show portions of the medical cleaning and disinfection apparatus that form no part of the claimed design.

1 Claim, 8 Drawing Sheets
